UNITED STATES PATENT OFFICE

LEWIS H. DAVIS, OF UPPER DARBY, AND RUSSELL T. KINGSFORD, OF WYNCOTE, PENNSYLVANIA, ASSIGNORS TO ATWATER KENT MANUFACTURING COMPANY, OF PHILADELPHIA, PENNSYLVANIA, A CORPORATION OF PENNSYLVANIA

LOUD-SPEAKER

Application filed April 28, 1930. Serial No. 447,786.

Our invention relates to amplifying telephones, loud speakers, or radio speakers, particularly of the type having a coil mounted upon and moving with a sound-reproducing diaphragm, specifically a hollow, truncated cone of suitable material.

In accordance with our invention, the small open end of the cone is reinforced or strengthened, and preferably also secured to the cone-actuating member, specifically a coil form, by co-operating elements or collars, preferably of metal, in engagement with the inside and outside surfaces of the cone respectively and in opposing or clamping relation.

The coil leads are preferably secured to the vibrating unit comprising the diaphragm and coil assembly within the length of a flange element, specifically a clamping collar extension.

More specifically, one of the elements or collars is an extension of, or integral with, the coil form, and the other collar is attached to or integral with a resilient cone-centering disc, or equivalent, attached at its center, for example, to a stationary support, specifically a cylindrical pole piece, or extension thereof.

Preferably and more specifically, the small end of the cone terminates in a re-entrant flange and receives the coil form, a rim or collar portion of the centering member clamping the flange against the coil form.

Further in accordance with our invention, prior to their engagement, co-operating surfaces of either the cone, or of the reinforcing collars, or both, are coated with glue, cement, or the like.

Our invention resides in the features of construction, combination and arrangement hereinafter described and claimed.

This application is a continuation in part of our copending application Serial #349,605, filed March 25, 1929.

For an illustration of some of the forms our invention may take, reference is to be had to the accompanying drawings, in which:

Fig. 1 is a side elevational view, with

parts in section, of an electro-dynamic speaker constructed in accordance with our invention.

Fig. 2 is a fragmentary view on enlarged scale of parts shown in Fig. 1.

Fig. 3 is a front elevational view on enlarged scale, of the cone-centering element shown in Fig. 1.

Figs. 4 to 8 inclusive, are detailed views, on enlarged scale, of modified forms of cone-supporting and actuating arrangements.

Referring to Fig. 1, to the rear wall 1 of a housing or casing member 2, is secured electro-magnetic structure comprising the field coil 3, disposed within the cup-shaped housing 4, preferably of magnetic material, the bolt 5 threadably engaging the central pole piece 6 and extending exteriorly of the housing 2 where it is engaged by the nut 7.

A spacing washer 8, or equivalent, of suitable thickness is disposed between the rear wall 1 of the housing and the back plate 9 of the magnet assembly. The bolts 10 pass through back plate 9, front plate or pole piece 11, and apertures in the supporting structure 12, tightening of nuts 13 threaded on bolts 10 clamping these elements together.

To the outer edge, or periphery of the cone 16, of any suitable material, as parchment, Chinawood, or the like, is intimately attached as by adhesive, a flexible supporting ring 17, of thin leather, impregnated cloth, or equivalent, which is clamped by bolts 18 between the flange 19 of housing 2 and a protecting element or guard ring 20.

Preferably and as shown, the supporting element 12 for the front end of the magnet assembly terminates in an outwardly extending flange 12^a, through which the bolts 18 pass, spacing washers 21 of suitable material being suitably interposed between the elements. To conceal flanges 19, 12^a, washers 21, etc. the guard element 20 is provided with the turned back edge 22. The apertures 23 in the casing 2, and openings 24 in

the magnet supporting member 12, prevent undue confinement of air to the rear of the cone 16.

Referring particularly to Fig. 2, to the small end of the cone 16 is attached the

cylindrical coil form 25, of insulating material, for example, having a slot or groove 26 in which is found the coil 27 traversed by currents varying at voice frequency. To prevent their engagement with the annular pole piece or front member 11 of the magnet structure, the leads 28 of the voice coil 27 are disposed in one or more grooves 29 in the coil form 25. The turned back flange or re-entrant edge 30 of cone 16 snugly receives the forward end of coil form 25 and is clamped thereon by the rim 31 of the cone-centering and supporting element 32. The angle of the flange 33 of the centering member 32 is substantially the same or equals the angle of and engages the inner surface of cone 16. Preferably the re-entrant edge 30 of the cone is coated on both sides with glue, cement or the like prior to engagement with the coil form 25 and clamping rim 31. The elements are held in proper position by rim 31 during the drying period and it is not necessary as in prior construction using glue alone to wait for the glue to harden before relieving the cone and coil form from pressure, as by removal from a press.

In the finished diaphragm and coil form assembly, the inner end of the conical diaphragm overlying the metal flange 33 is rigidly attached thereto so that at this region within the length of the flange the diaphragm is incapable of flexure. This same condition obtains with the other modifications hereinafter described.

The leads 28 from the voice coil which may be extensions of the flexible conductor forming the coil or flexible wires connected to the terminals of the coil are secured by any suitable means, as by a dab of adhesive, or cement, or as indicated by a strip of adhesive tape 14, to the vibrating unit consisting of the diaphragm and coil assembly to that part of the diaphragm overlying and stiffened by the flange 33.

The free ends of the leads are connected to suitable terminals 15, 15 which may as illustrated be mounted upon a block of insulation secured to the supporting structure 50 12. The inner ends of the leads 28 are attached or anchored at a point within the extent of the rigid conical flange 33 and are there fixed with respect to the coil 27, and partake of movements or vibrations equal to 55 the movements or vibrations of the coil.

Heretofore it has been the practice to construct the centering element or spider 32 of fibre and to glue it directly to the cone. Aided in some cases by atmospheric conditions, 60 the strain incident to the large amplitude of movement characteristic of this type of speaker has broken or weakened the connection between the cone and the centering element effected solely by glue.

65 Referring to Fig. 3, the centering member

32 is preferably of duralumin or other suitable material, as aluminum, brass, steel, etc. It is preferably formed from a circular flat disc, the rim 31 and flange 33 being formed by spinning, drawing, or equivalent operation. The top or spider portion of the element is formed by a piercing or stamping operation and its resilience may be increased, if desired, as by suitable hammering operations. The inner spring-arms 34, and the outer spring-arms 34' are so proportioned in length as to more equally distribute the load between them and to permit greater amplitude of movement of cone 16. A machine screw 35 or equivalent passes through the central aperture 36 of the centering member 32 and threadably engages an extension 37 of the pole piece 6, clamping the spider tightly against the projection, and supporting the cone and coil form so that the latter is freely movable rectilinearly in the air gap between the pole pieces 6 and 11. The centering of the coil permits its movement without change in position transversely of the air gap, and precludes the possibility of its coming into contact with either or both pole pieces. Since the small end of the cone is rigidly connected to the coil form and the base or large end of the coil is supported by the flexible ring 17, all parts of the cone or diaphragm vibrate at amplitudes equal to the amplitudes of movement of the coil itself. The metal spider is not subject to the warping and stretching of fibre board spiders heretofore commonly used.

In the modification of my invention shown in Fig. 4, the coil form 25^a is of metal, as German silver, brass, or the like although it may be of insulating material, as fibre, bakelite, etc. The coil 27 may be wound on the form in a region of smaller diameter, between the rolled-back edge 38 and shoulder 39. The coil form of Fig. 2 may be also constructed in like manner and of metal. This modification differs from that of Fig. 2 in that the rim 31 of the centering member 32 engages the coil form rather than the re-entrant edge of the cone 16. Preferably glue or equivalent is used to strengthen engagement between the coil form 25^a and the rim 31, in which event it is desirable to use a paper gasket therebetween to obtain a fast and durable union of these elements. The cone is wedged between the flange 33 and rim 31 of the centering member 32 and a clamping ring 40 which preferably has portions extending parallel to flange 33 and rim 31. The leads 28 of the coil are insulated from and attached to the flange 33 by tape, for example, the free ends of the leads extending from the point of connection to suitable fixed terminals as previously described. As in the prior modification glue, cement or equivalent is or may be utilized to supplement the clamping rings to effect rigidity of 12

the assembly structures. To stiffen the thin metal winding form 25^a, both ends may be rolled, the edge remote from the cone being turned outwardly to hold the windings in place, as above described.

In the modification of my invention shown in Fig. 5, the winding form 25^b is integral with the centering member 32, and may, as in the preceding modification, be of metal, with or without a portion of smaller diameter for receiving the turns of the voice-coil 27. The reinforcing ring 40, preferably of metal, holds the re-entrant portion 30 of the cone 16 tightly against the periphery of the winding form 25^b, the joint being reinforced by glue or cement, if desired, as previously described. The flange 41 adhesively attached to the cone 16 reinforces and stiffens it. The coil leads 28 are anchored to the diaphragm within the conical length of flange 41 and extend therefrom to fixed terminals 15, 15.

The arrangement shown in Fig. 6 is similar to that of Fig. 2 in that the spider 32 and the flange engaging the inner face of the cone 16 are integral, the spider of the centering member 32, however, in this modification being larger. The external diameter of the form 25^c in the region engaged by the winding 27 is the same as that of coil form 25, the greater diameter of the portion engaging the re-entrant edge 30 of the cone being effected by turning back the metal to form the reversely extending portion 42. Preferably, and as shown, the turned back portion is formed with a flange 43 co-operating with the flange 33 of the centering member 32 further to strengthen and reinforce the connection between the cone 16, the centering member 32, and the coil form 25^c. The leads from the coil are secured to and insulated from the flange 43 in any suitable manner and from that point of mechanical connection extend from the vibrating system to binding points mounted upon a stationary support, as disclosed in Fig. 1. If necessary or desirable, the metal coil form of Figs. 4, 5 or 6 may be slotted, as indicated in Fig. 6. The apertures or slots 44 ordinarily will extend longitudinally of the coil form.

When the cone is of a more or less brittle material, as Chinawood, the construction shown in Fig. 7 may be used to advantage. The edge of the cone is not re-entrant as in the preceding modifications, but is bent outwardly to form a cylindrical extension or flange 45 which is clamped between the rim 31 of the centering member 32, and the collar portion 46 of the coil form 25^a, preferably of metal. The collar portion may, if desired, and particularly when the resilient spider 32 is of larger area, be of suitably larger diameter than the portion on which the coil 27 is wound and preferably is

formed with a flanged extension 43 which engages the outside surface of the cone. Further to strengthen the small end of the conical diaphragm 16, the centering member 32 may be provided with flange 33 extending outwardly from the rim to suitable extent. The diameters of rim 31, and collar 46, and the thickness of the cone 16 are preferably such that appreciable force must be applied to the centering element 32 to effect the relation between the parts shown in Fig. 7. The leads 28 as indicated are attached to the flange 45 which overlies the small end of the cone, extending therefrom to binding posts or equivalent. As in the prior modifications the union between these members or their equivalent may be strengthened by suitable adhesive.

In the modification of my invention shown in Fig. 8, the centering member 32 is generally similar to that of Fig. 7 in that it is provided with a cylindrical portion 31 and an angularly disposed flange portion 33. The coil form 25 is, however, in this modification directly engaged, and internally, by the rim 31 and forced into contact with the outwardly extending cylindrical extension 45 of the cone 16. The collar 47 clamps the cone end 45 against coil form 25 and the portion of the cone adjacent this region against flange 33 of the centering member 32. The coil leads 28 are secured to the flanged portion of the outer collar 47 in a manner similar to that described for the other modifications.

In Figs. 2, 4, and 5 to 8 inclusive, engagement between the coil form, cone, etc. may be in any sequence or simultaneous, as may be desired or expedient in view of the assembling tools, or machines, etc.

What we claim is:

1. A telephonic sound reproducer comprising a diaphragm substantially of the shape of a truncated cone and terminating in an inwardly directed flanged portion, annular reinforcing collars engaging opposite sides of and clamping said flanged portion between them, and a reticulated centering disc integral with one of said collars and extending across the area bounded thereby.

2. A telephonic sound reproducer comprising a diaphragm substantially of the shape of a truncated cone and terminating in a re-entrant flange, a coil form having a collar portion operatively related to one side of said flange, an element having a collar portion operatively related to the other side of said flange and cooperating with said first named collar portion to secure the diaphragm to said coil form, and a reticulated centering disc integral with and extending across the area bounded by one of said collar portions.

3. A telephonic sound reproducer comprising a conical diaphragm, a cylindrical

coil form, means to secure the coil form to the small end of said diaphragm comprising a cap having a cylindrical portion and a resilient end portion comprising a slotted disc, and means to secure the central portion of said disc to a stationary member.

4. A telephonic sound reproducer comprising a conical diaphragm having a re-entrant flange at its small end, a coil form over-lapping said flange, and a cap member having a rim portion cooperating with said coil form to effect operative connection therewith of said flange, and an end portion slotted to provide spring arms.

5. A telephonic sound reproducer comprising a truncated cone diaphragm having a re-entrant flange at the small end thereof, a coil form received by said flange, and a metal cap having a collar portion cooperating with said coil form to secure said flange thereto, and an end portion slotted to provide spring arms.

6. A telephonic sound reproducer comprising a truncated cone diaphragm having a re-entrant flange at the small end thereof, a coil form received by said flange, and a metal cap having a collar portion effecting connection of said flange and said coil form, a flange having substantial area of contact with said cone adjacent the re-entrant flange thereof, and an end portion slotted to provide spring arms.

7. A telephonic sound reproducer comprising a diaphragm substantially of the shape of a truncated cone terminating in a flanged portion, a coil form over-lapping said flange, a cap-member having a rim portion cooperating with said coil form to effect operative connection therewith of said flange and a resilient end portion, and means to secure said cap at substantially the center of said end portion to a stationary member.

8. A telephonic sound reproducer comprising a conical diaphragm, a cylindrical coil form, means to secure the coil form to the small end of said diaphragm comprising a cap having a cylindrical portion and a resilient end portion comprising a disc, and means to secure the disc substantially at its central portion to a stationary member.

9. In telephonic apparatus, a vibrating unit comprising a conical diaphragm and a coil, a form for said coil, means for securing said form to said diaphragm comprising a conical flange element engaging said diaphragm, and a flexible connection from said coil to the external circuit and attached to said unit within the conical length of said flange.

LEWIS H. DAVIS.
RUSSELL T. KINGSFORD.
